HEAT EXCHANGER

Addison Y. Gunter, Larchmont, N. Y., assignor to
American Locomotive Company, New York,
N. Y., a corporation of New York

Application April 9, 1942, Serial No. 438,260

1 Claim. (Cl. 257—237)

This invention relates to heat exchangers.

An object of the invention is to provide a simplified heat exchanger in which the exchange is accomplished between two fluids having series flow in two or more passes.

Other and further objects of this invention will appear from the following description, the accompanying drawing and the appended claim.

Referring to the drawing forming a part of this application, Figure 1 is a view of a heat exchanger embodying the present invention, shown partly in side elevation and partly in section on the line I—I of Fig. 2, parts being shown in full and parts being broken away, the heat exchanger being foreshortened; Fig. 2 is an end view of the exchanger as viewed from the right of Fig. 1; Fig. 3 is an end view of the exchanger as viewed from the left of Fig. 1, parts being broken away; and Fig. 4 is a foreshortened view of the exchanger, shown partly in plan and partly in section on the line IV—IV of Fig. 2, parts being shown in full.

The heat exchanger, indicated generally by the reference numeral 1, includes a shell 2 closed at its forward end by a header 3 and at its rear end by a header 4. Shell 2 is a hollow cylinder of plate metal. The exchanger is shown in Fig. 1 in a horizontal position and it will be so described, it being understood that it may be disposed in other positions if desired.

Header 3 is shown as a built-up structure and includes a tube sheet 5 which fits in the forward end of shell 2 and is welded thereto, as clearly designated in Fig. 1 by the reference numeral 6. The tube sheet 5 has an upper opening 7 and lower opening 8, vertically aligned in the vertical center plane of the exchanger.

Header 4 is shown made of two castings secured together and includes a tube sheet 9 secured to the rear end of the shell. In the present instance the tube sheet 9 includes a cylindrical flange 10 which is butt-welded to the end of the shell, as clearly shown in Fig. 1, the weld being designated by the reference numeral 11. Tube sheet 9 has openings 12 and 13 in line respectively with openings 7 and 8.

The exchanger further includes cylindrical sleeves 14 which are disposed with their rear ends in openings 12 and 13. Each sleeve 14 extends forwardly from tube sheet 9 through shell 2, the upper one passing through opening 7 and the lower one through opening 8 and forwardly of the tube sheet 5 a predetermined distance, the portions forward of the tube sheet 5 forming part of the header 3. These portions may be separate

from the portions in the shell, if desired. Sleeves 14 preferably have a sliding fit in openings 12 and 13 and are expanded in openings 7 and 8, a tongue and groove connection 15 being provided to prevent escape of shell fluid through openings 7 and 8. The sliding fit in openings 12 and 13 allows free expansion and contraction of sleeves 14. The forward end of each sleeve 14 is threaded.

10 A pipe fitting 16 is connected to the side wall of each sleeve 14 forward of tube sheet 5, each pipe fitting opening into its sleeve. It is contemplated that the top fitting 16 in Fig. 1 will form the inlet to the exchanger for shell fluid and the bottom fitting 16 will form the outlet. The fittings are vertically aligned and oppositely directed. The portions of sleeves 14 forward of tube sheet 5 form header chambers, the top portion an inlet and the bottom portion an outlet chamber.

15 Tube sheet 9 further includes two openings 17 and 18 (see Fig. 4) horizontally aligned on the horizontal center plane of the exchanger, openings 7, 8, 12, 13, 17 and 18 preferably all being 20 of the same size. The exchanger further includes sleeves 19 which are disposed with their rear ends expanded into openings 17 and 18, tongue and groove connections 20 being provided to prevent displacement of sleeves 19 from their openings 17 and 18. Sleeves 19 extend forwardly from tube sheet 9 but stop well short of tube sheet 5, opening at their forward ends directly into shell 2. They are thereby free to expand and contract.

25 Header 4 further includes a hollow cover 21 divided by a diagonal wall 22 into two compartments 23 and 24. Compartment 23 affords communication between the upper sleeve 14 and one sleeve 19, and compartment 24 affords communication between the lower sleeve 14 and the other sleeve 19. Tube sheet 9 and cover 21 are secured together by stud bolts 25, a gasket 26 providing a fluid-tight connection.

30 Tube sheet 5 further includes two orifices 27, 45 one in line with each of the openings 17 and 18 but of smaller diameter.

The heat exchanger further includes a U-bend fin tube 28 having four finned tubes or legs 29, one in each of the sleeves. The free 50 ends of the tube are the forward ends of the legs in sleeves 14, the rear ends of these legs extending one into compartment 23 and the other into compartment 24, and each being connected to a U-bend 30 disposed therein. Another straight leg is connected to and extends

forwardly from each U-bend 30 through the sleeves 19, these legs extending at their forward ends through the orifices 27, and being threaded at their forward ends. In each orifice 27 is a flanged coupling 31 surrounding and secured to the adjacent leg, the flange engaging the inner face of tube sheet 5. Couplings 31 are threaded exterior of the shell, and nuts 32 secured thereon hold the flange in fluid-tight engagement with the tube sheet 5. The legs of the U-tube, being secured only at their forward ends, are free to expand and contract, the U-bends 30 floating each in its compartment.

A U-bend 33 connects the forward ends of the legs in sleeves 19, unions 34 forming the connections.

Flanged couplings 35 surround and are secured to the forward ends of the legs in sleeves 14 by tongue and groove expanded connections 36. An orificed cap 37 is screwed on the threaded end of each sleeve 14, a coupling 35 extending through each cap orifice and being threaded at its forward end. A nut 38 is threaded on the coupling in engagement with the cap 37, the nut and cap closing the forward end of the sleeve 14, and the coupling flange engaging the inner face of the cap.

The U-bend tube may be removed from the exchanger through the rear end by first removing the cover 21, the unions 34 and the nuts 32 and 38, the flanges of the couplings 31 and 35 being of smaller diameter than the inside diameter of the sleeves to permit withdrawal of the couplings through the sleeves.

The inlet end of tube 28 is designated by the reference numeral 39. Thus the tube fluid makes four series passes in the exchanger before reaching the outlet, indicated by the reference numeral 40. Similarly the shell fluid makes four series passes, entering the upper fitting 16, passing through the upper sleeve 14 into compartment 23 and therefrom through the correlated sleeve 19 into shell 2, therefrom through the other sleeve 19 into compartment 24 and therefrom through the lower sleeve 14 and out through the lower fitting 16.

It will be understood from the foregoing description that the heat exchanger of the present invention presents a simple construction free from damage due to expansion and contraction of parts and permitting heat exchange by series flow through four passes of fluid. However it

is contemplated that the heat exchange may be accomplished with a greater or lesser number of passes.

While these has been hereinbefore described an approved embodiment of this invention, it will be understood that many and various changes and modifications in form, arrangement of parts and details of construction may be made thereto without departing from the spirit of the invention, and that all such changes and modifications as fall within the scope of the appended claim are contemplated as a part of this invention.

The invention claimed and desired to be secured by Letters Patent is:

A heat exchanger for heat transfer between two fluids, comprising a shell; a header at one end thereof; a tube sheet at the other end thereof; two short and two long sleeves extending longitudinally in said shell, said header having a header plate and a detachable cover for said plate having two compartments, said sleeves, at one end thereof, extending into orifices formed in said plate, a long and a short sleeve thereby communicating with each compartment, said short sleeves opening at their other ends into said shell, said long sleeves extending through said tube sheet and having end portions therebeyond; closures for said end portions, said end portions each having an orifice providing one an inlet and the other an outlet, said sleeves, compartments and shell cooperating through intercommunication thereof for series flow therethrough of one of said fluids, said short sleeves being secured in said plate and said long sleeves slidably engaging said plate and being secured in said tube sheet, whereby said sleeves are free for expansion and contraction; and a fin tube having U-bends disposed one in each of said compartments and legs extending through said sleeves from the ends of each U-bend, the legs extending through said short sleeves further extending through said tube sheet and having end portions extending therebeyond, said tube further having a U-bend disposed exterior of said shell connecting said tube end portions, the legs extending through said long sleeves extending through said closures thereof, one providing an inlet and the other an outlet for said other fluid, said legs and U-bends co-operating through intercommunication thereof for series flow therethrough of said other fluid.
